UNITED STATES PATENT OFFICE.

FREDOLF J. PETERSON, OF SALEM, OHIO, ASSIGNOR TO THE AMERICAN CASE & REGISTER COMPANY, OF SALEM, OHIO, A CORPORATION OF OHIO.

DETACHABLE HINGE.

1,021,885.

Specification of Letters Patent.

Patented Apr. 2, 1912.

Application filed October 6, 1911. Serial No. 653,268.

To all whom it may concern:

Be it known that I, FREDOLF J. PETERSON, a subject of the King of Sweden, residing at Salem, in the county of Columbiana and State of Ohio, have invented a new and useful Improvement in Detachable Hinges, of which the following is a specification.

My invention relates to improvements in detachable hinge designed to be employed wherein it is desirable to frequently separate or detach the hinge members for any desired purpose, as for instance the removal of the leaves from a credit cabinet; and the objects of my improvement are, first, to provide a simple structure, and second, to provide a structure, easily operated and convenient for the purpose designed. These objects and advantages together with other objects readily apparent to those skilled in the art, I attain by the construction illustrated in the accompanying drawings, although my invention may be embodied in a variety of other mechanical forms, the construction illustrated being chosen by way of example.

In the accompanying drawing: Figure 1 is a perspective view showing the hinged members detached from each other. Fig. 2 is a transverse section of the lower hinged member shown in Fig. 1. Fig. 3 is a longitudinal section of said lower hinged member. Fig. 4 is a perspective view showing the hinged members connected together. Fig. 5 is a sectional view of the upper hinged member and its connecting plate showing an element connected to said hinge member.

Similar numerals of reference indicate corresponding parts in all the figures of the drawing.

In the accompanying drawing, 1 represents the relatively fixed hinged member or leaf and 2 the movable hinged member or leaf; to which hinged member or leaf is attached the swinging element 3 which so far as the present invention is concerned may be a credit account leaf or it may be any other article, such as a door or cover. It is well understood that leaf hinges are provided with connecting knuckles which are connected together by means of what is commonly known as hinge pins or pintles. I have illustrated a single form of hinge, one member provided with two connecting knuckles and the other member with one;

but it will be understood that the number may be increased without departing from the nature of the present invention, reference being had to the strength of the hinge designed to be used or employed. The hinge member or knuckle 1 is provided with the longitudinal bores 3^a and 4, the bore 3^a being of a diameter less than the diameter of the bore 4, said bores being of different diameters for the purpose hereinafter described. In the present instance I employ what might be termed a yoke to couple the hinge members or knuckles together, which yoke consists of the coupling or pintle portion 5, the retaining or holding portion 6 and the handle or knob portion 7, all preferably made of a single piece.

In Fig. 3 I have illustrated the yoke placed in the position to couple the hinge members together or in the same position illustrated in Fig. 4, which figure shows the hinge members coupled together. When it is desired to detach the hinge members for any purpose, the yoke proper is moved longitudinally a sufficient distance to entirely remove the pintle portion 5, so as to detach said pintle portion from the connecting knuckle 8 formed upon the hinge member 2, at which time the hinge member 2 is free to be lifted from the hinge member 1 and detached therefrom. In order to prevent the yoke from becoming entirely detached at any time the retaining or holding portion 6 is provided with the head 9, which head may be formed by swaging the end of the retaining or holding portion 6, but the particular manner of forming the head 9 is immaterial, the only object is to form the head so as to limit the movement of the yoke in one direction by means of the head 9 coming in contact with the shoulder 10, which shoulder separates the bores 3 and 4. It will be understood that the movements of the yoke proper are so limited that the pintle portion never becomes detached from the hinge member 1 so that when the hinge member 2 is placed in position to couple the two hinge members together, the pintle portion is in position to be passed through the aperture formed in the knuckle 8, by which arrangement the hinge members may be quickly coupled together and also easily detached from each other for any purpose.

In Fig. 5 I have illustrated the hinge member 2 connected to the swinging ele-

ment 3 by means of a rivet 11, which rivet is passed through the flanges 12 and the stiffening or strengthening bar 13. I have illustrated this construction simply to show 5 one method of connecting the hinge member 2 to the swinging element.

It will be understood that so far as the present invention is concerned it is immaterial as to how the hinge members are connected to the relatively fixed object and the 10 relatively swinging one.

It will be understood that the handle or knob 7 will also serve the purpose of limiting the sliding movement of the yoke in one 15 direction and the head in the opposite.

For the purpose of allowing the pintle portion of the yoke to be moved a sufficient distance to remove said pintle portion from the connecting eye or flange 8, the shoulder 20 10 is located at one side of the recess into which the eye-flange 8 is seated, so that when the head 9 strikes against the shoulder 10 the pintle portion will be entirely removed from the eye flange 8.

Having fully described my invention what I claim as new and desire to secure by Letters Patent, is—

1. A detachable hinge consisting of two 30 members, one of said members provided with bores having different diameters, a yoke consisting of pintle, retaining and handle portions, said retaining portion provided with a head, substantially as and for the purpose specified.

2. In a detachable hinge, the combination 35 of hinge members provided with knuckles, a sliding yoke carried by one of the hinge members and adapted to couple the opposite hinge member to the member carrying the

yoke, substantially as and for the purpose 40 specified.

3. In a detachable hinge, the combination of hinge members provided with eye knuckles, a sliding yoke carried by one of the hinge members and adapted to couple the 45 opposite hinge member to the member carrying the yoke, and means for limiting the movements of the yoke, substantially as and for the purpose specified.

4. In a detachable hinge, the combination 50 of two members, one of said members provided with a recess adapted to receive the other hinge member, the member provided with a recess having longitudinal bores of different diameters, a yoke consisting of 55 pintle retaining and knob portions, said retaining portion provided with a head, a shoulder located between the bores having different diameters, said shoulder located at one side of the recess into which the eye 60 member of the hinge is entered, substantially as and for the purpose specified.

5. In a detachable hinge, the combination with separable hinge members, of a pintle member movable into and out of engagement with one of the hinge members, said pintle member undetectably connected to one of said members and provided with a handle adapted to join the pintle and hinge 65 members together, substantially as and for 70 the purpose specified.

In testimony that I claim the above, I have hereunto subscribed my name in the presence of two witnesses.

FREDOLF J. PETERSON.
